[57] CLAIM

The ornamental design for a row boat hull, as shown and described.

DESCRIPTION

FIG. 1 is a perspective view of a row boat hull showing my new design;

FIG. 2 is a left side elevational view thereof and a mirror image of a right side elevational view;

FIG. 3 is a top plan view thereof;

FIG. 4 is a front elevational view thereof and a mirror image of the rear elevational view thereof; and

FIG. 5 is a bottom plan view thereof.
